[57] CLAIM

The ornamental design for a water closet tank, as shown and described.

DESCRIPTION

FIG. 1 is a top perspective view of a water closet tank showing our new design;
FIG. 2 is a front elevational view thereof, the rear elevational view being the mirror image thereof;
FIG. 3 is a left side elevational view thereof, the right side being the mirror image of the left side;
FIG. 4 is a top plan view thereof; and
FIG. 5 is a bottom plan view thereof.
The broken line representations of fitting holes in FIG. 5 are for purposes of illustration only.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 298,565

DATED : November 15, 1988

INVENTOR(S) : Herbert V. Kohler, Jr. and Mary J. Reid

It is certified that error appears in the above-identified patent and that said Letters Patent is hereby corrected as shown below:

On the Title page

Under UNITED STATES PATENT [19] - Kohler, Jr. should read
Kohler, Jr. et al,

[75] Inventor: Herbert V. Kohler, Jr., Kohler, Wis.
should read

[75] Inventors: Herbert V. Kohler, Jr., Kohler;
Mary J. Reid, Sheboygan, both of Wis.

Signed and Sealed this
Twenty-third Day of March, 1993

Attest:

STEPHEN G. KUNIN
